UNITED STATES PATENT OFFICE.

CHARLES W. EISELE, OF FLINT, MICHIGAN.

LAMP-DIMMER.

1,335,727.

Specification of Letters Patent.

Patented Apr. 6, 1920.

Application filed July 10, 1916. Serial No. 108,515.

To all whom it may concern:

Be it known that I, CHARLES W. EISELE, a citizen of the United States, residing at Flint, in the county of Genesee and State 5 of Michigan, have invented certain new and useful Improvements in Lamp-Dimmers, of which the following is a specification.

My invention relates to improvements in lamps and more particularly to means 10 for regulating the intensity of the illumination. The invention is particularly applicable to head lights for automobiles, motor boats, traction cars, or other vehicles, but may be adapted to lamps for other purposes.

15 The object of the invention is to simplify the structure as well as the means and mode of operation of such devices whereby they will not only be cheapened in construction, but will be more efficient in use, positive in 20 operation, economical, easily and quickly operated, and unlikely to get out of repair.

One of the primary objects of the present invention is to provide means for varying the intensity of the light through a gradual 25 scale whereby any degree of illumination within certain limits may be attained.

With the above primary and other incidental objects in view, as will more fully appear in the specification, the invention 30 consists of the features of construction, the parts and combinations thereof, and the mode of operation, or their equivalents, as hereinafter described and set forth in the claims.

35 Referring to the drawings, Figure 1 is a sectional view of the assembled lamp embodying the invention forming the subject matter hereof. In this view the regulating device or interceptor is shown in its dimming or operated position. Fig. 2 is a similar view showing the regulating device or interceptor in retracted or inoperative position. In the construction shown in Fig. 2 the regulating member is adapted to be mechanically operated while in Fig. 1 it is 40 adapted for electrical control. Fig. 3 is a similar view showing a modification in which in lieu of moving the regulating member or interceptor the lamp or illuminating 45 member is shifted in relation thereto. Fig. 50 4, is a detail sectional view on a reduced scale showing means for operating the lamp stem.

Like parts are indicated by similar characters of reference throughout the several 55 views.

Referring to the drawings, 1 is the lamp housing having the usual glass face 2. The transparent face 2 is carried in the usual frame 3 which forms a removable closure 60 for the housing 1. Within the housing is located a reflector 4 of parabolic form. Positioned at the focal point of the parabolic reflector 4 is the usual incandescent bulb or illuminating member 5. The illuminating member 5 in the construction shown in Figs. 1 and 2 is stationarily secured upon a supporting shaft or stem 6 projecting through an opening 7 in the apex of the parabolic reflector 4. 70

The high degree of intensity or illumination secured by such construction is due to the reflection of the rays of light emanating from the incandescent bulb or illuminating member 5 and reflected from the inner face 75 of the parabolic reflector 4. The reflector 4 is so proportioned that the light will be condensed or will be projected in substantially parallel rays, the direction of the rays of light being indicated by dotted lines in 80 Fig. 1.

Without the use of the reflector 4 the lamp or illuminating member 5 affords but a limited degree of illumination. Therefore 85 by intercepting more or less of the rays of light emanated from the lamp and permitting only a limited number of rays to reach the reflector 4, the brilliancy or intensity of the illumination may be regulated throughout a gradual scale from low to high power. 90

To intercept the rays of light and thereby regulate the intensity of the reflected light, there is provided a reciprocating sleeve or interceptor 8 mounted upon the shaft or stem 6 and having its forward end bell shaped or flared as at 9 to inclose the bulb or illuminating member 5 when in its forward position. By referring to Fig. 1 it will be seen that when the sleeve 8 is shifted forward the bell shaped extremity will inclose the lamp and intercept the rays of light which would otherwise reach the reflector 4. No light being permitted to reach the reflector, the only illumination afforded will be that of direct light, in a forwardly direction as indicated. In its retracted position, as shown by dotted lines, the interceptor or screen will not interfere with the illuminating of the reflector 4 and the full lighting value or intensity of the reflected 105 light may be had. By adjusting the inter- 110

ceptor or sleeve 8 to various positions intermediate those shown by dotted and solid lines, Fig. 1, a greater or less area of the reflector 4 may be utilized, thereby varying 5 the degree or intensity of illumination accordingly.

Any suitable means may be employed for reciprocating the sleeve or interceptor. It 10 may be operated manually or by electrical or mechanical means as may be found best suited to its conditions of use. In Fig. 1 there is shown an electrical solenoid 10 to the core 11 of which is attached an arm 12 secured to the sleeve or interceptor 8. There 15 is also attached to a finger or lug 13 upon the sleeve or interceptor a retracting spring 14, the opposite end of which is secured to the interior of the housing 1. The construction is such that the spring 14 normally 20 tends to draw the sleeve or interceptor 8 rearwardly to expose the full area of the reflector 4 to the illuminator 5. However, upon the energizing of the solenoid 10 the attraction of its core will draw the sleeve 25 or interceptor forward to the position shown by full lines in Fig. 1 and against the tension of the retracting spring 14. As shown in Fig. 1, the sleeve or regulating member intercepts all the rays of light which would 30 otherwise be reflected from the parabolic reflector 4 and the only illumination available is that of direct light in a forwardly direction.

The construction shown in Fig. 2 is quite 35 similar to that shown in Fig. 1 except that in lieu of the solenoid 10 and the retracting spring 14 operated in opposition one to the other there is employed a gear sector 15 pivoted at 16 and engaging a series of rack 40 teeth 17 upon the sleeve or interceptor 8. The gear sector 15 may be oscillated by any suitable actuating means such as the link 18 to reciprocate the sleeve 8 to and from the bulb or illuminator 5. By this means 45 the interceptor or sleeve may be adjusted to any intermediate position, thereby affording different degrees of illumination.

To secure the best result and the highest 50 degree of illumination it is essential that the center of illumination shall coincide with the focal point of the reflector. In Figs. 1 and 2 the construction is such that the lamp or illuminating member is fixed in its proper focal position in relation with 55 the reflector 4. However, in Fig. 3 there is shown a modification in which the lamp is movable to and fro into and out of the focal position. By shifting the lamp or illuminating member to and from the focal point 60 the angle of incidence and therefore the angle of reflection of the rays of light is changed and the intensity of the illumination is gradually varied. In this construction the interceptor or sleeve 19 is fixed in 65 relation with the reflector 4 and the hous-

ing 1. The lamp 5 is carried upon a movable support 20 slidingly mounted within the sleeve 19. In its rearmost position the lamp will be positioned within the flaring extremity of the sleeve or interceptor whereby none of its rays will reach the reflecting surface of the reflector 4. The general construction is quite similar to that shown in Figs. 1 and 2 except that the lamp is shifted in relation with the interceptor or sleeve 70 75 whereas in the preceding figures the interceptor is moved in relation with the lamp. Any suitable means may be employed for shifting the lamp in the construction illustrated in Fig. 3. For instance, it may be 80 manually operated or may be operated by either electrical means, as shown in Fig. 3, or by mechanical means as in Fig. 4.

In Fig. 4 the reference characters correspond to those employed in Fig. 2 and designate the same parts excepting that the reference characters have prime marks and the lamp stem with the lamp is shifted.

From the above description it will be apparent that there is thus provided a device of the character described, possessing the particular features of advantage before enumerated as desirable but which obviously is susceptible of modification in its form, proportion, detail construction, or arrangement of parts without departing from the principle involved or sacrificing any of its advantages.

While in order to comply with the statute the invention has been described in language 10 more or less specific as to certain structural features, it is to be understood that the means and construction herein described comprise but one mode of putting the invention into effect and the invention is 10 therefore claimed broadly in any of its possible forms or modifications within the scope of the appended claims.

Having thus described my invention, I claim:

1. In a lamp, a housing, a reflector in the housing having an opening in the apex thereof, a lamp, a substantially cylindrical stem extending through said opening and secured at its rear end to the housing and carrying said lamp at its front end, a sleeve longitudinally slidable on said stem and having its front end flared to inclose the lamp, said flared end of the sleeve being movable through the reflector opening, and means to move the sleeve longitudinally of and on the stem.

2. In a lamp, a housing, a reflector in the housing, a lamp, a substantially cylindrical stem connected to the lamp, an elongated 12 sleeve surrounding the stem and having a flared end closely and conformably surrounding the lamp, the sleeve and stem having relative longitudinal movement, means to rigidly mount one of said last named ele- 136

- ments, and means to effect instantaneous relative longitudinal sliding movement between the sleeve and stem.
3. In a lamp, a housing, a reflector in the housing, a lamp, a substantially cylindrical stem connected to the lamp, an elongated sleeve surrounding the stem and having a flared end closely and conformably surrounding the lamp, the sleeve and stem having relative longitudinal movement, means to rigidly mount one of said last named elements, a spring connected to the sleeve and to the housing, an arm connected to the movable one of said elements and extending laterally thereof, a core carried by the arm 15 and a solenoid extending axially of the reflector and disposed to the rear of the reflector and in front of said arm.
- 5 In testimony whereof I have hereunto set my hand this 26th day of June, A. D. 1916. 20
- CHARLES W. EISELE.
